UNITED STATES PATENT OFFICE.

ELMER A. PURDY, OF AMBOY, ILLINOIS.

SOCKET FOR USE IN CONCRETE WORK.

No. 899,185.

Specification of Letters Patent. Patented Sept. 22, 1908.

Application filed January 22, 1908. Serial No. 412,220.

To all whom it may concern:

Be it known that I, ELMER A. PURDY, citizen of the United States, residing at Amboy, in the county of Lee and State of Illinois, have invented certain new and useful Improvements in Sockets for Use in Concrete Work, of which the following is a specification.

The present invention relates to improvements in building construction of that character in which concrete or similar plastic material is employed and wooden studs or like members must be connected to the concrete portion.

More specifically the invention resides in the provision of a novel construction of socket member which is peculiarly designed so as to produce a firm bond with the plastic material and form a socket to receive the tenon of a stud or like member.

For a full understanding of the invention and the merits thereof and also to acquire a knowledge of the details of construction and the means for effecting the result, reference is to be had to the following description and accompanying drawings, in which:

Figure 1 is a perspective view of a socket member embodying the invention. Fig. 2 is a similar view showing the bottom of the socket member. Fig. 3 is a perspective view showing the device applied. Fig. 4 is a longitudinal sectional view through the socket member.

Corresponding and like parts are referred to in the following description and indicated in all the views of the drawings by the same reference characters.

Specifically describing the present embodiment of the invention, the numeral 1 designates a tubular casing designed to have one end thereof embedded in the base 2 of concrete or similar plastic material as shown in Fig. 3, the concrete extending upwardly within the casing to a level with that upon the outside of the casing. The portion of the casing projecting above the base 2 forms a socket to receive the tenon of a stud 3 or like member and an opening is formed in one side of the casing through which a fastening member 4 may be driven into engagement with the tenon.

The end of the tubular casing 1 which is embedded in the plastic base 2 is provided with a laterally extending hollow shoe comprising the sides 5 and the inclined top 6 and the space within the shoe is filled with the plastic material so as to obtain a firm bond therewith. It will also be observed that the top 6 of the shoe has an opening 7 therein designed to receive a wire cable 8 or similar tie member which is embedded in the plastic base 2 in order to reinforce the same. It is designed that these cables 8 connect spaced socket members so as to prevent spreading of the building should the floor become cracked. Attention is also directed to the fact that a drain opening 9 is formed in one side of the casing 1 immediately above the surface of the floor or base 2 to prevent accumulation of moisture within the socket and consequent rotting of the timber. It will thus be apparent that the present device when embedded in the concrete portion of the building forms a secure bond therewith and also projects beyond the concrete and constitutes a socket to receive the tenon at the end of a stud or like member.

Having thus described the invention, what is claimed as new is:

1. A socket for connecting a stud to a base of plastic material, the said socket comprising a tubular casing one end of which is designed to receive the stud while the opposite end is designed to be embedded in the plastic base and is provided with means for obtaining a firm bond therewith. 85

2. A socket for connecting a stud to a base of plastic material, the said socket comprising a tubular casing one end of which is designed to be embedded in the plastic base and is provided with a laterally projecting hollow shoe for obtaining a firm bond therewith. 90

3. A socket for connecting a stud to a base of plastic material, the said socket comprising a tubular casing one end of which is designed to receive the stud while the opposite end is designed to be embedded in the base of plastic material and is provided with a laterally projecting hollow shoe for obtaining a firm bond therewith, the hollow shoe being formed with spaced sides and an inclined top. 95 100

4. A socket of the character described com-

prising a tubular casing adapted to have one end thereof embedded in the base of plastic material, and a tie member connected to the said end of the tubular casing.

5. A socket of the character described comprising a tubular casing provided at one end with a laterally extending shoe and adapted to have the said end and shoe embedded in

the base of plastic material, and a tie member connected to the shoe.

In testimony whereof I affix my signature in presence of two witnesses.

ELMER A. PURDY.
